(57) **CLAIM**

The ornamental design for a wind control cover for elevator, as shown and described.

DESCRIPTION

FIG. 1 is a front, top and right side perspective view of a wind control cover for elevator, showing our new design;
FIG. 2 is a front elevational view thereof;
FIG. 3 is a rear elevational view thereof;
FIG. 4 is a right side elevational view thereof;
FIG. 5 is a top plan view thereof;
FIG. 6 is a bottom plan view thereof;
FIG. 7 is a cross-sectional view thereof; taken along line 7-7 of FIG. 2; and,
FIG. 8 is a perspective view thereof showing the state in use. The broken line showing is included for the purpose of illustrating environment and forms no part of the claimed design.
